UNITED STATES PATENT OFFICE.

JOHN FLAMMANG, OF ST. LOUIS, MISSOURI, ASSIGNOR TO OTTMAR G. STARK, OF ST. LOUIS, MISSOURI.

PROCESS OF MAKING PISTONS.

1,347,450.

Specification of Letters Patent.

Patented July 20, 1920.

Application filed May 23, 1918. Serial No. 236,189.

To all whom it may concern:

Be it known that I, JOHN FLAMMANG, a citizen of the United States, residing at St. Louis, Missouri, have invented a new and useful Process of Making Pistons, of which the following is a specification.

This invention relates to the art of manufacturing pistons.

An object of the invention is to improve the art of manufacturing pistons whereby pistons may be produced to utilize the resiliency of the metal of which the pistons are composed in an efficient manner in order to maintain close contact with the cylinder walls making use of piston rings or packing unnecessary.

A specific object of the invention is to provide a method for use in the manufacture of pistons, whereby the upper portions of the pistons will coöperate effectively with the cylinder to prevent the passage of gas, steam or the like between the piston and the cylinder without the use of piston rings or packing.

Other objects will be apparent by the following description in which reference is made to the accompanying drawings, illustrating a piston in several stages of its construction in accordance with the present invention, and in which—

Figure 1 is an elevation partly in section illustrating a casting that may be used in the construction of the piston body.

Fig. 2 is an elevation illustrating the casting after one or more stages or steps of treatment.

Fig. 3 is a view of the casting after the upper portion thereof has been expanded or placed under tension and set in its expanded shape, so that when the piston is finished and placed in the cylinder it will impart pressure against the cylinder wall all around.

Fig. 4 is a view of the piston body while the upper portion thereof above the wrist pin is held under tension ready for the casting to be finished as to its circumferential surface, tensioning of the lower portion of the piston body being prevented by the wrist pin.

Fig. 5 is a view illustrating the piston body held under tension within the cylinder in which the treatment of the body of the piston is finished and made ready for the head plate to be applied thereto.

Fig. 6 is an elevation of a finished piston made in accordance with my present invention.

Fig. 7 is a sectional view of a piston mounted within a cylinder.

By my present invention the body of the piston is made from a casting so that the upper portion of the casting in its finished form is expanded from its original size to a size in excess of the diameter of the cylinder for which the piston is intended; and then compressed and placed under tension and finished to a size equal to the size of the cylinder for which it is intended so that when the piston body is placed within the cylinder it will impart pressure against the wall of the cylinder all around, thus dispensing with the use of piston rings and packing. The upper portion of the piston is set in its expanded shape by heat, or in any other desired manner as by hammering, and the wrist pin is mounted in the expanded piston leaving the upper portion of the piston free to expand and contract and coöperate properly with the wall of the cylinder.

As shown, the piston body is composed of a lower ring 1, an upper ring 2, connections 3 integrally uniting the upper and lower rings and bosses 4 integral with the connections 3. The original casting is provided with arms 5 extending inwardly from diametrically opposite sides above the plane of the bosses 4. Projections 6 are integral with the arms 5 and are spaced apart so that they may be capable of movement toward each other when the upper ring is compressed as hereinafter explained.

The first stages or steps in the construction of the piston by my improved process consist in cutting the upper ring as shown at 7 so as to divide the upper ring into separate segmental sections which are adapted to press against the wall of the cylinder in which the piston operates by the resiliency of the metal of the piston. After the upper ring has been cut or split into segmental sections the upper portion of the piston body is spread apart and placed under tension in any desired manner, as by inserting a wedge 10 or block 8, or other appropriate form of implement, between the bosses 4. Next the material of the piston is set in its expanded shape by subjecting the piston body to heat or by hammering so that the molecular

structure is changed. As a result of such treatment after the spacer 8 is removed the material will be held in its new shape, because of the treatment to which the piston body is subjected.

After the spacer 8 is removed alined holes 9 are formed through the connections 3 and the bosses 4 and the wrist pin 10 is mounted in the holes thus formed and is held in such position by set screws 11.

Next the connections 3 above the wrist pin and the segmental sections of the ring 2 are placed under tension. This may be effected as shown by inserting a bolt 12 in holes in the extensions 6 and turning the nut on the bolt until the segmental sections of the ring 2 are turned to the desired positions and the proper tension is given to the connections 3 above the wrist pin. While the casting is thus held under tension the periphery of the casting is ground or turned and finished to a size in which the lower portion of the casting is of slightly less diameter than the diameter of the cylinder for which the piston is intended and in which the diameter of the ring 2 while under compression or tension is of a size equal to the diameter of the cylinder for which the piston is intended. The dotted lines 13 (Fig. 4) approximately indicate the surface lines to which the piston is to be finished. After the periphery of the piston has been finished to give the upper ring a diameter the same as the diameter of the cylinder for which the piston is intended, while the material is held under tension as described, the piston is placed within a cylinder 14 (Fig. 5) of the same diameter as the diameter of the cylinder for which the piston is intended, thus holding the upper portion of the piston compressed under tension after the bolt 12 is removed.

The upper portion of the ring 2 is then cut away below the arms 5 at right angles to the axis of the piston and, if desired, an internal groove 15 is formed in the ring 2. Also, either before the piston is placed within the cylinder 14 or after removal therefrom, as desired, a number of circumferential grooves 16 are formed in the lower ring 1, the same being adapted to receive an oil or lubricant whereby the piston and the cylinder wall are lubricated during operation of the piston.

The head or top plate 17 is connected to the ring 2 and interlocked therewith in some desired manner, as by a flange 18 engaging in the groove 15; or, as preferred, by keys 19 seated in slots in the open ends of the ring 2 and engaging in grooves in the top plate; or, if desired both the flanges 18 and the keys 19 may be employed as shown in Fig. 7. Said keys therefore are effective to hold the top plate in connection with the piston body and, since the keys ex-

tend across the slits 7 said keys are also effective to close the spaces between the open ends of the ring 2 and thus prevent passage of gas through said spaces.

The upper edge of the ring 1 is beveled to provide a scraping edge 20, which will scrape the oil from the cylinder wall during upward movement of the piston; and the lower edge of the ring 2 is beveled to provide a scraping edge 21 to scrape the oil from the cylinder wall during downward movement of the piston.

As clearly illustrated in Figs. 6 and 7, the finished piston has a body composed of an upper ring of slightly larger diameter than the diameter of the cylinder for which the piston is intended; and when the piston body is compressed within the cylinder the segmental sections of the upper ring will impart against the cylinder wall all around sufficient pressure to prevent the passage of gas or steam while the spaces between the ends of the segmental sections of the upper ring are closed against the passage of gas or steam by the keys 19.

Plainly the order in which many of the stages of treatment are performed in the manufacture of the piston is not of great importance and the order of such performance may be varied in many particulars without departure from the principle of the invention as set forth in the appended claims.

I claim:

1. The process of making a piston which consists in forming a piston body with an upper ring and a lower ring which are integrally united; splitting the upper ring to form segmental sections; expanding the upper portion of the piston body; treating the piston body to set the material in its expanded shape; compressing the expanded portion of the piston body; and finishing the same while under compression.

2. The process of making a piston which consists in forming a piston body with an upper ring and a lower ring which are integrally united; splitting the upper ring to form segmental sections; expanding the upper portion of the piston body; treating the piston body to set the material in its expanded shape; compressing the expanded portion of the piston body; and finishing the same while under compression to a diameter equal to the diameter of the cylinder for which the piston is intended.

3. The process of making a piston which consists in splitting the upper end of a piston body into segmental sections, expanding the segmental sections; setting the material in its expanded shape; and finishing the segmental sections to a size so that when the piston is placed within a cylinder the segmental sections will press outwardly in all directions against the cylinder wall.

4. The process of making a piston, which comprises forming a piston body of a lower ring and an upper ring composed of a number of segmental sections integrally united 5 with the lower ring; expanding the segmental sections; setting the material in its expanded shape; tensioning the segmental sections; and finishing the exterior surfaces of the segmental sections to conform to the 10 curvature of the wall of the cylinder so that when the piston is placed within the cylinder the segmental sections will press outwardly in all directions against the cylinder wall.
- 15 5. The process of forming a piston which consists in forming a piston body of a lower ring, and an upper ring integrally connected with the lower ring; splitting the upper ring into segmental sections; holding 20 the material under tension; treating the material to set the same in its tensioned shape; compressing the upper ring under tension after said treatment; and finishing the piston while the same is compressed under tension.
- 25 6. The process of forming a piston which consists in forming a piston body of a lower ring, and an upper ring integrally connected with the lower ring; splitting the upper ring into segmental sections; holding the material under tension; treating the material to set 30 the same in its tensioned shape; compressing the upper ring under tension after said treatment; and finishing the piston while the same is compressed under tension to a size in which the upper ring is of the same diameter as the diameter of the cylinder for which the piston is intended.
- 35 7. The process of forming a piston which 40 consists in forming a piston body of a lower
- ring, and an upper ring integrally connected with the lower ring; splitting the upper ring into segmental sections; holding the material under tension; treating the material to set the same in its tensioned shape; compressing the upper ring under tension after said treatment; finishing the piston while the same is compressed under tension to a size in which the upper ring is of the same diameter as the diameter of the cylinder for which the piston is intended; and connecting a top plate to the piston body. 45
8. The process of forming a piston which consists of forming a piston body of a lower ring and an upper ring, and integral connections uniting the upper and lower rings; splitting the upper ring into segmental sections; mechanically forcing said connections apart to place them under tension; heating the piston body to set the material in its 50 changed shape; forcing the segmental sections of the upper ring toward each other to place the material under tension; and finishing the piston. 55
9. The process of forming a piston which 60 consists of forming a piston body of a lower ring, an upper ring, and integral connections uniting the upper and lower rings; splitting the upper ring into segmental sections; mechanically forcing said connections apart to 65 place them under tension; heating the piston body to set the material in its changed shape; forming alined holes through said connections after the same have been subjected to heat; fixing a wrist pin in said holes; 70 mechanically drawing the segmental sections of the upper ring toward each other to place the material thereof under tension; and finishing the piston. 75

JOHN FLAMMANG.
